UNITED STATES PATENT OFFICE.

JOHN E. GILSON, OF PORT WASHINGTON, WISCONSIN, ASSIGNOR TO GILSON MANUFACTURING COMPANY, OF PORT WASHINGTON, WISCONSIN.

CONTACT FOR INTERNAL-COMBUSTION-ENGINE IGNITERS.

1,192,887.

Specification of Letters Patent.

Patented Aug. 1, 1916.

Application filed March 30, 1914. Serial No. 828,333.

To all whom it may concern:

Be it known that I, JOHN E. GILSON, a citizen of the United States, and resident of Port Washington, in the county of Ozaukee and State of Wisconsin, have invented certain new and useful Improvements in Contacts for Internal-Combustion-Engine Igniters; and I do hereby declare that the following is a full, clear, and exact 10 description thereof.

My invention refers to igniter mechanism for internal combustion gas engines, its object being to provide means whereby the contact members of the igniter may be adjusted relative to each other in order to take up wear and to preserve the proper spark-gap, whereby the life of the mechanism is increased indefinitely. Practice has demonstrated that wear upon the contact members due to various causes will result and that, under ordinary conditions, after the faces of said members have been removed, the distance of the spark-gap is increased to such an extent as to reduce the efficiency of 20 the device or render it inoperative and, under such conditions the arms carrying the contact members have to be renewed at considerable expense. By providing the carrying arms with adjustable contact members 25 the above objectionable features are entirely overcome and the life of the device is thus increased indefinitely.

With the above objects in view the invention consists in certain peculiarities of construction and combination of parts as hereinafter set forth with reference to the accompanying drawings and subsequently claimed.

In the drawings Figure 1 represents a face 40 view of a pair of igniter arms embodying the features of my invention with certain parts in section to more clearly illustrate structural features, and Fig. 2, a detailed cross-section of the same, the section being indicated by line 2—2 of Fig. 1.

Referring by characters to the drawings, 1 represents the insulated fixed arm of a make and break spark mechanism, and 2 the shiftable companion arm, which shiftable

arm is pivotally mounted and under spring 50 tension in opposition to a stop-lug 3. The shiftable arm is controlled by a trip mechanism of any well known type, which mechanism forms no part of my invention and is therefore not shown. Both the shiftable 55 and fixed arms are provided with transverse recesses or apertures 4, into which apertures are adjustably fitted contact members in the form of plugs 5, 5'. The opposite companion contact faces of the plugs are adapted to make and break the ordinary electric circuit, whereby a spark is generated. These correlated contact members are adjusted to provide the proper spark-gap and thereafter locked in their adjusted positions by set- 65 screws 6.

Attention is called to the fact that the recesses in the arms extend therethrough and that the plugs or contact members 5, 5', are interchangeable, whereby the sparking 70 points may be reversed, if desired, for renewal. It is also obvious that, while I have shown both of the contact members adjustable, in some instances I may, without departing from the spirit of my invention, 75 utilize only a single adjustable contact member.

The above described arrangement illustrates one exemplification of my invention in detail, it being understood that said invention may be varied within the knowledge of skilled mechanics to accomplish the end in view, which is to provide adjustable contact bodies, whereby they may be moved to compensate for wear due to filing or cleaning the engaging points. It is also understood that the contact members may be formed from any suitable metal of highly conductive properties such as platinum alloy or the like.

I claim:

In a structure of the class described the combination of a swinging contact arm and a fixed contact arm, said arms being provided with bores adapted to aline, cylindrical contact plugs of uniform diameter throughout slidable in the bores, said plugs having each of the ends thereof adapted for

abutting engagement with an end of the other plug whereby said plugs are reversible and clamping means engaging said plugs to hold them in the bores.

5 In testimony that I claim the foregoing I have hereunto set my hand at Port Washington, in the county of Ozaukee and State

of Wisconsin in the presence of two witnesses.

JOHN E. GILSON.

Witnesses:

A. R. BOERNER,
OLAF ELTON.
